UNITED STATES PATENT OFFICE.

EDWARD HEIN, OF GRAND RAPIDS, MICHIGAN, ASSIGNOR TO FOOT REYNOLDS COMPANY, OF GRAND RAPIDS, MICHIGAN, A CORPORATION OF MICHIGAN.

DAY BED.

Application filed April 12, 1924. Serial No. 706,078.

To all whom it may concern:

Be it known that I, EDWARD HEIN, a citizen of the United States, residing at Grand Rapids, in the county of Kent and State of Michigan, have invented certain new and useful Improvements in Day Beds, of which the following is a specification.

My invention relates to improvements in, so-called, "day beds" and its objects are: 10 first, to provide a means whereby the bed springs and tick in the auxiliary part of the bed may be readily and easily raised and lowered with the least possible strain upon the actuating parts, and, second, to provide 15 a means whereby when the bed part of the auxiliary frame is elevated it will be held absolutely and reliably in position, and whereby when the bed part is lowered for sliding it under the primary bed, (not here 20 shown) it may be lowered sufficiently to protect the bed clothes and tick from contact with the frame of the primary bed.

I attain these objects by the construction shown in the accompanying drawing, in 25 which Fig. 1 is a sectional elevation of my bed frame upon the line 1—1 of Fig. 2. Fig. 2 is a plan of the bed frame, and, Fig. 3 is a 30 sectional end view of the bed frame on the line 3—3 of Fig. 1 with the bed spring frame and the tick in place in elevated position.

Similar reference characters indicate similar parts throughout the several views.

In the construction of this bed I make a 35 rectangular frame having upright sides 1 supported by cross ends, as indicated in Figs. 1 and 2. I pivotally mount a standard 2 near each end of and at one edge of one of said sides 1, as at 2'. The standards 40 should be so formed that a line drawn from 2' to 7 and thence to 3' will form an acute triangle, with the point 3' so positioned that its relative height from the bottom of the frame will not be materially varied when 45 the standards are swung from the positions shown by their solid lines into the positions indicated by their dotted lines, or vice versa.

To operate these standards to raise and lower the bed 9 I pivotally mount a lever 6 50 upon the side 1, midway between the said standards, as at b. I then pivotally connect one end of each of the connecting rods 4 and 5 with said lever, as at 5 and 5', one above and one below the pivotal bearing of 55 the lever, and likewise connect the other

ends of said connecting rods with the standards at 3', thus rendering it impossible for a dead center to be formed at any point in the swinging movements of said standards, rendering it possible to exercise the maximum of force from the lever 6 upon the said standards at each and every point in their movement when raising or lowering the bed.

At the other side of the bed frame I pivotally mount plain standards, as indicated at 8, and connect the standards 2 therewith by means of cross bars or rods 7 and 11. The rod 11 is used simply as a brace to assist to hold the two uprights in proper alinement, and the cross rods 7 not only assist to hold these uprights in proper alinement, when raising and lowering the standards for raising and lowering the bed springs and tick, but they form supporting bearings for the 75 spring frame, as indicated at 9" in Fig. 3.

When the parts 4, 5 and 6 are in the position shown in solid lines in Fig. 1, the uprights 2 are held in their elevated position for holding the auxiliary bed springs and tick upon the same plane with the tick on the primary bed, as indicated in Fig. 3, but when the lever 6 is carried over into the position indicated by its dotted lines a, the connecting rods 4 and 5 will be carried into the positions indicated at b and c, and the standards will be carried into the positions indicated at d, when the spring frame 9" and the tick 9 will be lowered into the position indicated by the dotted lines 9' in 90 Fig. 3.

In Figs. 1 and 3 I have shown a supporting rod 10 designed to hold the standards 2 in proper vertical position when elevated, but when the stop e is used the rod 10 is 95 not essential for this purpose, though even then I deem it of great service in strengthening the sides of the bed frame.

It will be noted that when the standards 2 are in the position indicated by their 100 dotted lines at d, the points of connection with the connecting rods 4 and 5 is so far above the pivotal bearings 2' of the standards that it requires but slight strain upon the lever 6 to move the lever from a to e 105 and raise the bed tick and springs into their uppermost positions, indicated in Fig. 3, and in this peculiar feature lies the germ of my invention, as by this construction I am enabled to lower the bed springs to the lowest 110

possible position, as upon the rods 2', bringing the tick well below the top of the frame 1, and when in this position it requires but small effort upon the lever 6 to raise the entire structure into the higher position indicated in Fig. 3.

As the difference in the sizes of the several elements in the construction of this bed is such as to render it impracticable to produce proper proportions upon a sheet of Patent Office Bristol board, I have shown Figs. 1 and 2 of my drawing severed at X and Z so as to show the frame in three sections, A, B and C, longitudinally, thus enabling me to show the patentable features more plainly than I could, otherwise, have done. Furthermore, as day beds are in common use I have refrained from showing more than the elements in the auxiliary part of the bed that I desire to secure by Letters Patent, leaving the main frame of the bed, or the settee part, unillustrated.

Having thus fully described my invention, what I claim as new in the art, is:

25 In day bed construction, a frame having vertically disposed side rails, a standard

30 pivotally mounted upon one of said side rails near each end and near the lower edge thereof, an arm integral with an extending to one side of each standard and so positioned that the vertical distance of the end of said arms will be positioned upon the same plane above the pivotal bearing of the standards whether the standards are in horizontal, or in vertical position, a lever pivotally mounted upon the rail between the standards, connecting rods pivotally connected at one end with the lever each side of its pivotal bearing, and pivotally mounted at the other ends upon the ends of the 40 arms on the standards, plain standards pivotally mounted upon the other bed rail in position to pair with the first named standards, and supporting beams secured to and connecting the upper ends of the standards 45 in pairs, all so mounted that the operation of the lever will cause the standards to raise, lower and support the bed and bedding upon the cross beams.

Signed at Grand Rapids, Michigan, April 50
9th, 1924.

EDWARD HEIN
